(57) **CLAIM**

The ornamental design for an “articulating display mount”, substantially as shown and described.

DESCRIPTION

FIG. 1 is a first isometric view of an articulating display mount.

FIG. 2 is a front view of the articulating display mount of FIG. 1.

FIG. 3 is a rear view of the articulating display mount of FIG. 1.

FIG. 4 is a bottom view of the articulating display mount of FIG. 1.

FIG. 5 is a top view of the articulating display mount of FIG. 1.

FIG. 6 is a first side view of the articulating display mount of FIG. 1; and,

FIG. 7 is a second side view of the articulating display mount of FIG. 1.

The broken lines shown in FIGS. 1-7 illustrate portions of the articulating display mount that form no part of the claimed design.

1 Claim, 7 Drawing Sheets
